UNITED STATES PATENT OFFICE

2,451,001

BRASSIÈRE

Leda I. Speiser, Chicago, Ill., now by marriage
Leda I. Lash

Application December 11, 1944, Serial No. 567,567

8 Claims. (Cl. 2—42)

1

My invention relates to brassières.

This invention has for one of its objects the provision of a new and improved garment capable of containing the breasts without the necessity of support from the shoulders.

Another object is to provide a brassière in which the body encircling element is an integral strip of material cut and folded to conform to the body contour.

Another object is to provide a brassière in which the breast encircling element is an integral strip of material cut and folded to conform to the breast contour.

Another object is to provide a brassière in which each breast element is constructed to conform to the size of the breast and attached to the body encircling element so that it contains the breast in its natural position comfortably and presents a pleasing appearance.

A further object is to provide a brassière in which the construction takes into account the bony framework of the body and certain natural tendencies.

There are other features residing in elemental combinations and particular construction of parts, all as will hereinafter more fully appear. The brassière is especially designed for the pendulous breast, but is adaptable to the small firm breast. It is understood that the invention is equally applicable to girdles, one-piece garments and analogous garments and that the body encircling element is applicable to bathing suits, sunsuits, sleeveless dresses, dancing costumes, princess slips, and analogous garments.

With these and other objects in view, this invention consists in the construction and novel combination of parts fully described hereinafter, illustrated in the accompanying drawings, and pointed out in the claims appended hereto, it being understood that various changes in the form, proportion, size and minor details of construction within the scope of the claims may be resorted to without departing from the spirit of the invention.

Further objects and advantages of the invention will be apparent from the description and claims.

In the drawings, in which my invention is shown,

Figure 1 is a perspective view of the complete brassière as it appears when worn;

Fig. 2 is a front view showing one side of the brassière formed and the other side showing the blank portion from which it is formed;

2

Fig. 3 is a rear elevational view of the rear side of the brassière laid out flat;

Fig. 4 is a plan view of the blank from which one of the breast pockets is formed;

Fig. 5 is a vertical medial section showing the brassière in position on the wearer;

Fig. 6 is a section on the line 6—6 of Fig. 1;

Fig. 7 is a section on the line 7—7 of Fig. 2;

Fig. 8 is a vertical section on the line 8—8 of Fig. 3;

Fig. 9 is a perspective view showing a strap connection;

Fig. 10 is a rear elevational view showing another form of pocket element;

Fig. 11 is a section on the line 11—11 of Fig. 10;

Fig. 12 is a plan view of a blank used in making a modified form;

Fig. 13 is a plan view showing the blank partially folded;

Fig. 14 is a view showing a further stage in the folding of the blank;

Fig. 15 is a view showing the blank completely folded and stitched;

Fig. 16 is a plan view of a blank used in making a further modification; and

Fig. 17 is a view showing the blank folded and stitched.

Referring to the drawings in detail, the construction shown comprises a body encircling portion A to which the breast pockets B are secured. The body encircling element (Fig. 1) fastens in the back at 4 and comprises three girdle members, a lower member 1 encircling the waist and extending underneath the pendulous part of the breasts, an upper member 2 encircling the chest above the breasts, and a middle member 3 extending over the breasts. The lower girdle member is considerably wider than the upper and middle girdle members 2 and 3. The lower girdle portion extends around the body underneath the breasts and fastens in the back. It forms a support for the breast receiving pocket elements B. The upper girdle member extends around the body above the breasts and fastens in the back. The upper edges of the elements B are secured to this upper girdle member. The middle girdle member extends across the upper portion of the breasts and thence extends around the body and fastens in the back.

The waist member 1 is the basic support of the garment and serves as the supporting attachment for the breast pockets B secured thereto along the lines 5. It encircles the bony framework of the body its entire length making a taut fastening possible and, because of the uniform shape of the

body at this point, tends to remain in position. The tendency of a garment at this point is to be pushed upward by breathing. This upward push operates against the downward pull at 5a (Fig. 5).

The chest member 2 encircles the bony framework along its entire length and may be securely fastened. It serves as a means of attachment for the upper edge of the breast receiving elements B. This member has a tendency to slip downward but at the point where it crosses the chest, the breast begins a convex curve and this downward movement is retarded.

The middle member 3 extends transversely across the breasts. It follows the inner contour of each breast, passes over and continues rearwardly, fastening independently at the back. The straps 3a and 3b of this member are free of any attachment to the members 1 and 2 and the elements B throughout their entire length. It gives shape and direction to the breast and relieves the breast element from strain on the parts adjacent the straps. The pendulous breast tends to shift back and forth slightly in a lateral direction. This natural tendency is accommodated by the gentle pressure exerted by the middle member 3 in its transverse direction.

Fig. 3 illustrates how the central or middle portion of the body encircling portion A is formed. The formation of the girdle members 1, 2 and 3 leaves an uncut upward projection portion D-E-F-G frusto-triangular in shape, the base G-F being an integral part of the lower member 1 and the upper part D-E being an integral part of the upper member 2. This uncut portion D-E-F-G superimposes the triangular area intermediate the breasts and provides support for the attachment of the proximal edges of the breast receiving pocket B.

In prevailing brassières, the lateral shifting of the breasts is offset by pulling them upward and forward to fit into cups of predetermined shape and size after the garment is fastened. This practice is to create the illusion of a larger and more pointed breast and has only its aesthetic effect to recommend it. This unnatural position of the breasts produces added strain to the shoulders and causes discomfort under the arm from the reverse pull. In this brassière, this lateral shifting is taken into account by providing ample space in the underarm portion of the breast element B. Further, it is secured to the waist member 1 by a horizontal seam 5. It is attached to the chest member 2 by a horizontal seam 5a. This mode of attachment leaves the distal portion of the breast element relatively free. It permits the breast its natural position and provides added comfort under the arm and a feeling of security from the pressure of several thicknesses of cloth. The construction of the breast receiving pocket exerts a minimum amount of pressure on the breast and the absence of an upward pull by a shoulder strap further minimizes this pressure.

The breast receiving element B is partially self sustaining by its shape and construction. To provide for lateral movement, the element is spheroidal in shape and the portion of greatest strength and thickness is made to coincide with the region of greatest weight and thickness. Because the element holds the breast in its natural state without changing the position or shape, there is no resistant force to overcome and it tends to remain in place.

As shown in Fig. 2 and as will be described more

fully hereinafter, all three of the girdle portions are of a single integral fabric folded so that they will extend in the desired direction. The fabric is slit as indicated at 6, 7 and 9 in Fig. 2 to provide the girdle members 1, 2 and 3, and the upper one of the strips thus formed is folded down about the dotted line 8 in Fig. 2 to form the double thickness. The slitting at 7 and 9 terminates at the points D, E, F and G, leaving an uncut portion frusto-conical in shape. In order to provide some adjustment for this member, a flap 17a is slit at the midline and the cut edges are finished with laced fastenings or other suitable fastenings 19a, and the flap thus formed is brought down and attached back of the intermediate portion D-E-F-G. This lowers the medial front line of the upper girdle member and improves its appearance. The lower girdle member may have its lower edge folded upward about the line 10 to form a hem 11 or a double thickness. This slitting at 7 and 9 for the upper and lower girdle portion leaves an intermediate strip which is used in forming the intermediate strap or girdle members 3. In forming this girdle member 3, the upper and lower edges may be folded over to provide hems 12 and 13 (Fig. 2). The medial front portion of this intermediate strip is successively pleated or folded along the lines 14-15, 14-16, 16-17, and 17-14, as shown somewhat in detail in Fig. 9 to bring the strap 3 successively to the position shown at 3a, 3b, 3c and 3d, and the pleats are stitched along the line 17-15 to arrange it so that the girdle member 3 will extend upwardly at an angle to the horizontal, as shown at the left-hand side of Fig. 2. When completely folded and stitched, this construction provides a small recess between the strip 3 and the opposed triangular portion 14-16-17, which triangular portion lies between the flaccid part of the breast and the body.

When the brassière is worn, this upward slant of the member 3 causes it to extend transversely to preserve the contour of the breast and to accommodate lateral movement. The tab or flap 17a formed between the slits 6 may be doubled by folding on the line 17b and turned down and stitched to the medial portion D-E-F-G of the body encircling element A.

Each breast element may be formed of a single integral piece of fabric, the blank for which is shown in Fig. 4. In forming the pocket, the inner half is cut along the line 20 shown in Fig. 4 and the edges overlapped and stitched along the lines 21 to provide a spheroidal portion. The line 20 is the determining dimension of the breast receiving pocket. It is the distance between the midline of the body and the midline of the breast. A circle is drawn using this distance as a radius and separating the circle at the center by a length sufficient to permit folding into a multiple thickness and shaping the semicircles into hemiconoidal members by folding along radial lines, or by slitting along radial lines and overlapping the edges. This produces a frustoconoidal member conforming to the breast contour more truly than a cone or sphere. No fabric is cut away. This contributes to sturdiness in construction, and the multiple thickness across the medial portion adds to comfort and a feeling of support. The outer half of the blank is folded along the lines 22-23-24-25 and sewed together to provide a spheroidal portion, completing the pocket element. The blank may then be folded along the dotted lines 26 and 27 shown in Figs. 1, 2 and 4 and sewed to provide a medial reinforced por-

tion. The pocket element is then sewed onto the girdle members along the dotted lines 5 and 5a shown in Figs. 1, 2 and 3.

In Figs. 10 and 11 is shown a construction of breast member 28 which may be substituted for that disclosed in the preceding figures. In this form, each breast member B' is elongated to extend around and fasten in the back. The breast element may be made substantially the same as described in connection with Figs. 1-9, incl., by folding and stitching along the lines 21, 26 and 27 and by folding along lines 22, 23, 24 and 25 of Fig. 4 and stitching along lines corresponding to lines 22 and 25. The elongated portion 29 is formed as an integral part of the breast element by extending the medial portion 30 as shown in Fig. 10. This elongated portion 29 provides a fourth girdle whereby the breast member may be adjusted independently of the other strap or girdle members.

The brassière construction shown in Figs. 12-15, inclusive, has only two girdle members, the upper chest girdle member 33 and the lower waist girdle member 33a. It may be formed from a single integral piece of fabric by folding and stitching. Fig. 12 shows the blank from which the brassière is formed. Fig. 13 shows a succeeding stage in the folding and forming operation. Fig. 14 shows a later stage, and Fig. 15 shows the final stage.

As shown in Fig. 12, the fabric is first slit along the lines 34-36 and 39-40. The lower portion forming the lower girdle member 33a is then folded along the line 41-42 to provide a double thickness, as shown in Fig. 13. The upper portions are then folded along the lines 43-44 and 43-44a to assume the position shown in Fig. 13. The upper portions are then folded along the lines 36-43b and 40-44c to assume the position shown in Fig. 14. The upper members are then folded along the lines 45-46 and 45-46a to cause them to assume the position shown in Fig. 15. The breast member is then secured in place by stitching 47 along the line 50-51-52-52'-51'-50', thus securing each laterally extending portion 48 to each vertically extending portion 49 along the line 50-51 and securing the superimposed portions from 51 to 51' together to form a four-ply central support or anchorage.

The construction shown in Figs. 16 and 17 is also a two-girdle construction. In this form, the blank is cut and slit along the lines 53-54 and 55-56, as shown in Fig. 16. The portions 57 and 58 which are to extend laterally, as shown in Fig. 17, are creased and folded or pleated along the lines 56-59, 56-60, 54-61 and 54-62 to cause the portions 57 and 58 to extend laterally to assume the position shown in Fig. 17. The breast members are then stitched to the girdle members and to the central support along the lines 65-66-67-68, thus securing the superposed plies firmly together to provide a firm central anchorage for the girdles.

In the construction shown in Fig. 15, the upper one of the girdle members comprises two strap members 33b extending laterally from the vertically extending connecting portion 49, the integral connecting members being folded to provide successively a medial portion having an inverted V-shaped upper edge 69-70-71 symmetrical about a vertical axis, two trapezoidal portions 72-73-70-75 having parallel vertical edges overlying portions of the V-shaped portion, the upper edges 75-70-75 of the trapezoidal portions extending from each other in V-formation.

In the construction of Fig. 17, the girdle means

comprise an integral piece of fabric shaped to provide upper and lower girdle members 57 and 58 and a vertically extending portion connecting the girdle members, each girdle member comprising two strap members extending laterally from the vertically extending connecting portion 76 to the folds 77-78-79 at the junction of the two strap members with the vertical member extending substantially at right angles to each other.

10 Further modifications will be apparent to those skilled in the art and it is desired, therefore, that the invention be limited only by the scope of the appended claims.

Having thus described my invention, what I claim and desire to secure by Letters Patent is:

15 1. A brassière comprising a lower girdle member extending around the body underneath the breasts, an upper girdle member extending around the body above the breasts, two breast pockets secured at their upper edges to the upper girdle member and at their lower edges to the lower girdle member, a third girdle member overlying the upper portion of the breasts, the front portions of said third girdle member lying intermediate the front of said upper and lower girdle members, said third girdle member comprising two strap members, and means for uniting said strap members in front comprising a portion symmetrical about a vertical axis and having 20 downwardly diverging side edges lying between the breast and body.

2. A brassière comprising girdle means and a pair of breast receiving elements secured thereto, said girdle means being shaped to provide upper and lower girdle members and a vertically extending portion connecting said girdle members, one of said girdle members comprising two strap members folded about a diagonal line and extending laterally from said vertically extending connecting portion, the folds at the junction of the two strap members with the vertical member extending substantially at right angles to each other, the upper portions of said breast elements being secured to said upper girdle member and the lower portions of said elements being secured to the lower girdle member.

3. A brassière comprising girdle means and a pair of breast receiving elements secured thereto, said girdle means being shaped to provide upper and lower girdle members and a vertically extending portion connecting said girdle members, the upper one of said girdle members comprising two strap members extending laterally from said vertically extending connecting portion, said vertical connecting portion being folded to provide successively a medial portion having an inverted V-shaped upper edge symmetrical about a vertical axis, two trapezoidal portions having parallel vertical edges overlying portions of said V-shaped portion on opposite sides of the axis of symmetry, the upper edges of said trapezoidal portions extending from each other in V-formation, said straps extending from the upper edges of said two trapezoidal portions, respectively.

4. A brassière comprising a central supporting portion lying between the breasts, a girdle member secured to said central portion for extending along the upper portions of the breasts and about the body, a second girdle member secured to said central portion for extending beneath the flaccid part of the breasts and about the body, a pair of breast-receiving elements secured to said girdle members, and two partition elements, one for each breast, each extending laterally from said central supporting portion and lying between the breast

and body and forming with the opposed portion of the upper girdle member a recess into which the breast extends.

5. A brassière comprising a central supporting portion lying between the breasts, a girdle member secured to said central portion for extending along the upper portions of the breasts and about the body, a second girdle member secured to said central portion for extending beneath the flaccid part of the breasts and about the body, a pair of breast-receiving elements secured to said girdle members, and two partition elements, one for each breast, each extending laterally from said central supporting portion and lying between the breasts and body and forming with the opposed portion of the upper girdle member a recess into which the breasts extend, said central supporting portion sloping downwardly and laterally on both sides.

6. A brassière comprising a body portion and a pair of breast receiving elements secured thereto, each breast-receiving element comprising fabric shaped to provide hemiconoidal portions on both sides of a vertical medial plane and an intermediate zone portion extending between and along said hemiconoidal portions from top to bottom to space and connect them, the apexes of said hemiconoidal portions being spaced a substantial distance apart.

7. A brassière comprising a central frontal portion lying between the breasts, two upper bands secured to and extending laterally in opposite directions from said central portion from a position between the breasts, two lower band portions secured to and extending laterally in opposite directions from said central portion from a position between the breasts, and two breast-receiving elements, one on each side of said central portion having their upper edges overlapping and directly secured to said upper bands and their lower edges directly secured to and overlapping said lower bands and their inner ends secured to said central portion.

5

8. A brassière comprising a medial layer of flexible material lying between the breasts, a breast-receiving element secured thereto on each side thereof, each overlapping a side edge of said medial layer and being secured thereto along a line spaced inwardly from the side edge of said medial layer to provide a space between said medial layer and the opposed portions of the breast-receiving element to receive the side portion of the breast, and girdle means including a layer of flexible material extending underneath the flaccid part of each breast, each breast-receiving element overlapping the upper edge of said layer and being secured thereto along a line spaced downwardly from the upper edge of said layer to provide a space between said layer and the opposed portion of the breast-receiving element to receive the lower portion of the breast.

LEDA I. SPEISER.
